CAPPING MACHINE

Everett S. Minard, San Francisco, Calif., assignor,
by mesne assignments, to The Pfaudler Co.,
Rochester, N. Y., a corporation of New York

Application August 26, 1940, Serial No. 354,200

9 Claims. (Cl. 226—92)

The present invention relates to improvements in a capping machine, and its principal object is to provide a machine for capping containers while they are in motion. Heretofore it has been the practice, in bottle-capping machines, to cause the bottle to come to a dead stop while applying the cap. This causes a certain amount of jerking, and particularly in milk bottles which have a large neck and are usually filled clear to the rim, considerable spilling of the milk over the top of the bottle.

In the present invention it is proposed to avoid this undesirable feature and to provide a capping means which allows the container to proceed at its regular rate of travel while the capping operation takes place.

More particularly it is proposed to provide a capping device that travels back and forth in synchronized relation to the travel of the bottles or containers, travelling along with the bottle during the capping operation and reversing its direction after the capping operation is finished to engage the next bottle or container, after the latter has reached a proper position for the beginning of the capping operation.

It is further proposed, for the purposes hereinabove set forth, to provide means for causing the capping device to follow an endless path in a vertical plane, the capping operation taking place while the capping device passes through the lower arc of its endless path.

It is further proposed to control the movement of the capping device in such a manner that the endless path described by its movement is oval or egg-shaped in form, the device travelling through the narrow portion of the oval during the capping operation, whereby more perfect timing and coaction is secured.

Further objects and advantages of my invention will appear as the specification proceeds and the novel features of my capping machine will be fully set forth in the claims hereto attached.

The preferred form of my invention is illustrated in the accompanying drawings forming part of this application, in which:

Figure 1 shows a fragmentary plan view of my machine, with part of the mechanism omitted;

Figure 2, a vertical section taken along line 2—2 of Figure 1;

Figure 3, a rear view of an actuating lever used in my invention;

Figure 4, an isometric view of a vertically sliding frame and its mounting;

Figure 5, a plan view of a bracket supporting the lever of Figure 3;

Figure 6, an isometric view of a second frame carried by the first frame with freedom of horizontal sliding movement;

Figure 7, an isometric view of a mounting plate 5 for the capping device; and

Figure 8, a projection diagram showing the respective paths taken by the capping device and the bottle to be capped.

While I have shown only the preferred form of my invention, I wish to have it understood that various changes or modifications may be made within the scope of the claims hereto attached without departing from the spirit of the invention. In the following description, reference will 15 be made particularly to a machine for capping milk bottles of the conventional type, but it should be understood that the principles of the machine may be applied to any other capping machine regardless of what kind of container is 20 to be capped.

Referring to the drawings in detail, and particularly to Figures 1 and 2 thereof, it will be noted that the disc or table 1 is supported on the ball bearing 2 and is fixed to a vertical shaft 3 which latter is held in vertical position by the two bearings 6 and 7 of the housing 4 supported at a suitable height by the legs 5. As will be seen from Figure 1, a second shaft 8 is supported vertically in spaced relation to the shaft 3 and carries a star 9 partly projecting over the table 1, and intended to time the travel of the bottles 41 on the table.

The shaft 8 is driven from the shaft 3 by means of gears 10 and 11, in the ratio of 2 to 1, the star turning twice as fast as the table, and the star having four notches for controlling the bottle travel, so that eight bottles will be fed to the capping device for each revolution of the table.

A crank shaft 12 is supported radially in the 35 wall of the housing by means of two bearings 13 and 14 forming part of the crank bracket 15 suitably bolted to the housing. The crank shaft carries at its inner end, a pinion 16 which meshes with the bevel gear 17, rigidly fastened to the shaft 3. This connection is in the ratio of 8 to 1, so that, when power is applied to the crank shaft 12 from any suitable source, the latter will rotate the shaft 3 in the specified ratio.

The crank shaft also serves as a driving means for the capping device, which latter is made to operate once for each operation of the crank shaft, so that the entire machine is designed and timed to cap eight bottles for one revolution 45 of the table, which corresponds to the number 55 of the table, which corresponds to the number

of bottles released by the star during the same period.

The bracket 15 supports two parallel vertical guide rods 18 which rise along the edge of the disc 1 to a considerable height above the latter and which are interconnected at the top by the tie-bar 19. A frame 20, shown in detail in Figure 4 and having an open center is slidably mounted with freedom of vertical reciprocating motion on the guide rods 18 and supports, in lugs 20', two horizontal rods or trunnions 25. Reciprocating motion is imparted to the frame 20 by means of the connecting rod 21 having its lower end connected to the crank of the crank shaft 12 by means of a suitable bearing, and having its upper end connected to the pin 22 secured to the frame 20 through ears 23.

A second frame 24, shown in detail in Figure 6, is fastened upon the first frame 20 with freedom of lateral or horizontal reciprocating movement. This second frame comprises a channeled vertical body section movable forward of the space between the guide-bars 18 and laterally-extending arms terminating in rearward extensions and perforated, as at 26, to ride on the horizontal rods 25.

A stud 27 projects from the rear face of the second frame 24 between the guide-rods 18 and serves as a means for transmitting crosswise reciprocating motion to the second frame. This stud is actuated by means of a lever 28, shown in detail in Figure 3. The lever 28 is secured relative to the guide-rods 18 by means of a bracket 29, shown in detail in Figure 5. The bracket is made in the form of an arch, and is fastened upon the guide-rods 18 approximately mid-way between the crank of the shaft 12 and the stud 27.

The lever 28 is secured upon the bracket 29 by means of the screw 30, as illustrated in Figure 2. Both ends of the lever 28 are forked, and the lower end is made to straddle the crank of the shaft 12, while the upper end of the lever is made to engage over the stud 27.

In this manner the connecting link 21 serves to impart vertical reciprocating motion to the first frame 20 which carries the second frame, while the link 28 serves to impart crosswise reciprocating motion to the second frame 24. Both the link 21 and the lever 28 are driven by the crank of the crank shaft 12.

Attention is called at this point to the peculiar action of the lever 28. It will be noted that the leverage on which the lever operates is subject to constant change, since the operative length of each lever arm changes with each change in position of the crank pin and the stud 27. Figure 2 shows the crank pin in its lowermost position, and in that position it engages the extreme lower end of the lever arm. As the crank pin rotates, it rises, and when it reaches its uppermost position, it engages the lever arm in the upper end of the fork, thereby considerably reducing the operative length of the lower lever arm.

At the same time the stud 27 is moved upward by the connecting link 21 with the result that it rises in the upper fork substantially to the upper extremity thereof, so that the operative length of the upper lever arm increases during the upward travel of the crank pin. Thus there is continuous variation in the relative lengths of the two lever arms. As shown in the drawing, in the position of Figure 2, the operative length of the lower arm exceeds that of the upper arm,

whereas for the extreme upper position of the crank pin, the reverse would be true.

This construction affects the curve described by the pin 27. At the beginning of the upward movement of the crank pin, the lateral throw of the upper lever arm is comparatively small, whereas toward the end of the upward movement and at the beginning of the downward movement, the lateral throw is relatively large, to gradually decrease again as the crank pin re-approaches bottom position. This causes the pin to describe an oval curve in a vertical plane substantially as shown at 45 in the development of Figure 8.

15 The second frame carries, in its channel, the mounting plate 32, illustrated in detail in Figure 7, which may be secured in any one of several positions by means of a pin 35 passing through a hole 36 in the mounting plate into any one of 20 a plurality of holes 37 in the second frame 24. The channel guides 33 hold the mounting plate with freedom of vertical sliding movement, and the different adjustments are provided to make the machine adaptable for handling various sizes 25 of bottles or containers.

The mounting plate 32 is provided with a hub 38 which supports the capping device 31, the latter being of conventional construction. It is apparent that the capper or capping device follows the same curve as the stud 27.

30 The capper may be briefly described as comprising a stem 50 secured upon the hub 38 so as to project downwardly therefrom and terminating at its bottom end in a head 51 adapted to 35 push a cardboard cap 52 into the bottle 41 when the capper descends.

The capper includes a housing 53 terminating in an apron 54 fitting over the top of the bottle. The caps are accommodated in a magazine 54' 40 and are successively positioned with respect to the bottle by means of a slide 55 operated by a bell crank lever 56, which in turn is operated by a pin 57 projecting from the stem 50. A spring, not shown, urges the housing downwardly on the stem.

45 Prior to each operation, a cap is in position underneath the head 51. As the housing strikes the upper end of the bottle, it is stopped in its downward movement, but the stem 50 continues its downward movement and pushes the cap into place. At the same time the pin 57 moves the slide 55 outwardly, allowing the caps in the magazine to drop. On reversal of the movement of the stem the head 51 retracts and the slide 55 positions another cap for the next operation.

50 The stem 50 of the capper, of course, describes the same oval curve as the pin 27, in a vertical plane, and it should be positioned, with respect to the traveling of the bottles, to make the vertical plane approximately tangent to the arc followed by the bottles, as indicated at 44 and 43 of Figure 8. This makes the two paths substantially coincide for a brief period, and it is during this period that the capping operation takes place.

55 Guide-rails 39 are provided for the on-coming bottles on the disc or table 1, and a guide-rail 40 guides the out-going bottles. The bottles are placed between the two guide-rails 39, and as the machine rotates, they progress toward the star 9.

60 The pockets in the star pick up the containers, one at a time, and properly space and time them with respect to the capper movement, and after capping, the bottles continue to travel on the disc to a clear place from which they are removed.

The synchronized action of the bottles and the capper is illustrated in the diagram of Figure 8 which also shows a development of the curve described by the capper. The point 42 denotes the center of the disc, and the arc 43 the path of the bottles on the disc. The straight line 44, which is substantially tangent to the arc, denotes the vertical plane in which the capper moves, describing an endless path traced in the oval outline, shown at 45.

Referring to the diagram, more particularly, the lower circle 46 denotes the travel of the crank pin of shaft 12 and of the lower end of the connecting rod 21. It is shown as being divided into twelve equal parts, as designated by the letters A to M, respectively. The horizontal lines A1 to G1 in the upper portion of the diagram, are spaced to correspond to the vertical movement of the pin 27 or the capping device during each one-twelfth of a revolution of the crank pin.

The diagonal lines passing through the point 30 represent movement of the lever 28 during the same intervals, and the points A2 to M2 at the intersections of the diagonal lines and the horizontal lines, denote the path of travel of the pin 27 or of the capping device.

In the central portion of the diagram, the arc 43 indicates the travel of the bottle, and the points with letters A3, B3, etc., denote advances of the bottle for each one-twelfth of a revolution of the crank pin on shaft 12, the total advance from A3 to A3 corresponding to one-eighth of a revolution of the table 1. The line 44 indicates the vertical plane in which the capper travels, and the broken line projected from points D2 to K2 of the oval 45 show the location and advance of the capper while the bottle travels from G3 to K3.

It will be noted that the arc of the disc is sufficiently large to cause a small portion thereof, located between the points E3 and J3, to substantially lie in the vertical plane 44. This leaves only a comparatively short space available for performing the capping operation, and explains the advantage of the rather sudden dip in the curve showing the path of the capper.

Referring to the oval curve, it will be noted, by comparison of characters, that the capping operation is performed between the points E2 and J2, that is, during that portion of the travel where the capper makes the decided dip in its oval path.

The development of the oval curve may be readily traced by following the characters, the circle 46 tracing the path of the crank pin, and the point 30 indicating the fulcrum of the lever 28. The horizontal lines A1 to G1 denote the vertical distance travelled by the crank pin during each one-twelfth of a revolution, and the diagonal lines indicate the corresponding horizontal travel due to the lever action.

It is apparent that instead of positioning the parts with respect to one another for the vertical plane 44 to be tangent to the arc 43, they might be changed slightly to cause the vertical plane to just barely intersect the arc, as indicated in the drawing, so that the slight difference in the paths is taken up on both sides of the vertical plane, and thereby reduced by one-half.

In operation, as each bottle reaches E3 of the arc 43, the capper reaches point E2 on the oval curve 45. It then applies the cap in a dipping movement, while it passes from point E2 of the oval curve to the point J2, the bottle in the meantime moving from point E3 to point J3. The bottle then continues its advance on the arc

43 while the capper follows the path of the oval curve until it again reaches point E2, at which time a new bottle has reached point E2 on arc 43. Thus both the bottle and the capper remain in continuous motion.

I claim:

1. In a container capping machine, a capping device, means for mounting the same with freedom of horizontal and vertical movement, a rotary shaft having a crank therein, a connecting link driven by the crank for imparting vertical movement to the device and a lever actuated by the crank for imparting horizontal movement to the device, the lever having a fixed fulcrum and sliding connection with the crank and the capping device to bring about variation in the relative operative lengths of the lever arms as the capping device moves vertically.

2. In a container capping machine, a pair of vertical standards, a frame mounted thereon with freedom of vertical, reciprocating motion, a second frame mounted on the first frame with freedom of horizontal reciprocating motion, a crank shaft mounted with respect to the two frames, a connecting rod between the crank and the first frame for imparting vertical reciprocating motion to the latter, a lever actuated by the crank shaft and operating the second frame to impart horizontal reciprocating motion to the latter and a capping device carried by the second frame.

3. In a container capping machine, a frame, means for vertically reciprocating the same, a second frame carried by the first frame with freedom of horizontal reciprocating movement, a crank shaft, a lever connection between the crank shaft and the second frame for reciprocating the latter and a capping device carried by the second frame.

4. In a container capping machine, a frame, means for vertically reciprocating the same, a second frame carried by the first frame with freedom of horizontal reciprocating movement and having a capping device supported thereon, a crank shaft, and a lever connection between the crank shaft and the second frame for reciprocating the latter, the lever having a fixed fulcrum and forked ends slidably engaging over the crank and the second frame to bring about variation in the lever throw for different positions of the first frame.

5. In a container capping machine, a housing, a shaft vertically supported therein, a second shaft horizontally supported in the wall of the housing, a pair of posts mounted on opposite sides of the second shaft, means for transmitting motion from the second shaft to the first shaft, a table on the first shaft having means for guiding containers past the two posts at intervals, a frame vertically reciprocable on the posts, a crank in the second shaft, a link connecting the crank and the frame for vertically reciprocating the latter, a second frame mounted on the first frame with freedom of horizontal reciprocating movement and having a pin projecting therefrom, a lever carried by the posts and having forked ends engaging over the crank and the pin for horizontally reciprocating the second frame, and a capping device carried by the second frame.

6. In a machine of the character described, a frame, means for mounting the same with freedom of vertical reciprocating movement, a second frame, a capping device carried by the second frame, means for mounting the same on the first

frame with freedom of horizontal reciprocating movement, a connecting rod for vertically reciprocating the first frame, a lever for horizontally reciprocating the second frame and a common crank for actuating both the connecting link and the lever.

7. In a machine of the character described, a frame, means for mounting the same with freedom of vertical reciprocating movement, a second frame, a capping device carried by the second frame, means for supporting the same on the first frame with freedom of horizontal reciprocating movement, a connecting rod for vertically reciprocating the first frame, a lever for horizontally reciprocating the second frame and a common crank for actuating both the connecting rod and the lever, the lever having sliding connection with the second frame and the crank for actuating the former at constantly varying leverages.

8. In a container capping machine, a housing, a shaft vertically supported therein, a second shaft horizontally supported in the wall of the housing, a pair of posts mounted on opposite sides of the second shaft, means for transmitting motion from the second shaft to the first shaft, a table on the first shaft having means for guiding containers past the two posts at intervals, a

frame vertically reciprocable on the posts, a crank in the second shaft, a second frame mounted on the first frame with freedom of horizontal reciprocating movement, means operated by the 5 crank for imparting a compound vertical and horizontal movement to the second frame, and a capping device carried by the second frame.

9. In a container capping machine, a housing, a shaft vertically supported therein, a second shaft horizontally supported in the wall of the 10 housing, a pair of posts mounted on opposite sides of the second shaft, means for transmitting motion from the second shaft to the first shaft, a table on the first shaft having means for guiding containers past the two posts at intervals, a frame vertically reciprocable on the posts, a crank in the second shaft, a second frame 15 mounted on the first frame with freedom of horizontal reciprocating movement, means operated by the crank for imparting a compound vertical and horizontal movement to the second frame, and a capping device carried by the second frame, the latter means including a lever mechanism and sliding connections therein for imparting horizontal movement to the second frame at continuously varying leverages.

EVERETT S. MINARD.
